(57) CLAIM

The ornamental design for a sandal, as shown and described.

DESCRIPTION

FIG. 1 is a top perspective view of a sandal;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depicting the sole on the bottom of the sandal in FIGS. 2, 3, 4, 5, and 7 form no part of the claim.

The broken lines depicting a region on the bottom side of the sandal in FIG. 7 form no part of the claim.

1 Claim, 5 Drawing Sheets
